UNITED STATES PATENT OFFICE.

CHARLES E. FLORES, OF BATTLECREEK, NEBRASKA.

FASTENING FOR CARRIAGE-CURTAINS OR THE LIKE.

SPECIFICATION forming part of Letters Patent No. 778,649, dated December 27, 1904.

Application filed December 12, 1903. Serial No. 184,996.

To all whom it may concern:

Be it known that I, CHARLES E. FLORES, a citizen of the United States, residing at Battlecreek, in the county of Madison and State of 5 Nebraska, have invented new and useful Improvements in Fastenings for Carriage-Curtains or the Like, of which the following is a specification.

This invention relates to fastenings for carriage-curtains and the like; and the primary object of the same is to provide an eyelet for coöperation with a carriage-securing button or knob with automatically-operating locking means for engaging the head of the button or 15 knob to prevent accidental separation of the curtain from the button.

A further object of the invention is to provide a fastening means in connection with a carriage-curtain to coöperate with a button or 20 knob, which is capable of being quickly operated to secure or release a curtain and which may be used with the ordinary form of button.

With these and other objects and advantages in view the invention consists in the construction and arrangement of parts, which will be 25 more fully hereinafter set forth.

In the drawings, Figure 1 is a detail perspective view of a fastening embodying the features of the invention and shown open. 30 Fig. 2 is a front elevation of the fastening shown closed. Fig. 3 is a horizontal section on line 3 3 of Fig. 2 of the fastening and a portion of the curtain to which it is applied arranged in operative relation to a curtain 35 button or knob.

Similar numerals are employed to indicate corresponding parts in the several views.

The numeral 1 designates a flat eyelet-plate having spurs or securing prongs 2 projecting 40 from the periphery thereof and insertible through a curtain 3 around the usual button-opening 4, as many of the fastenings being employed as there are openings in the curtain. The prongs 2 are bent against the inner side 45 of the curtain, and, as shown by Fig. 3, may be drawn over the periphery of an annular wear-plate 5, forming a reinforce at the inner portion of the curtain around the opening 4.

The flat eyelet-plate has a keyhole-slot 6 50 formed eccentrically therein, the eccentricity

of this slot permitting the curtain to be drawn down to tighten it when secured. The eyelet-plate 1 also has an outstanding lug or projection 7, having its one end 8 forming a shoulder in relation to the plate. This lug or projection 7 is integral with the plate, being formed by slitting the plate and bending outward a portion of the metal thereof, thereby leaving a slot or opening 7' in the plate. A latch 9 is pivoted at one end to the plate 1 at 60 a point opposite the lug or projection 7 and formed with a slot or throat 10 to fit over the shank 11 of a curtain button or knob 12. The latch 9 is constructed of spring metal and is attached to the plate to one side of the slot 6, 65 the lug or projection 7 being on the other side of the said slot adjacent to the periphery of the plate 1. The latch is formed with a projecting arm 13, terminating in an outwardly-bent finger-piece 14, the upper shorter edge 70 15 of the arm contacting with the shoulder 8 of the lug or projection 7 when the latch is closed. The arm 13 of the latch is long enough to extend over the periphery of the eyelet-plate 1 for convenience in operating 75 the same, and when said latch is closed the upper terminal of the slot or throat 10 therein forms, with the lower reduced portion of the keyhole-slot 6, a circular opening, as shown by Fig. 2, of less diameter than the head of 80 the button or knob 12.

The curtain having the improved fastening applied thereto is pulled down sufficiently to cause the head of the button or knob 12 to pass through the upper enlarged portion of 85 the keyhole-slot 6, the latch 9 having been first opened or thrown back, as shown by Fig. 1. The curtain is then released, and the device thereon pulls the shank of the button or knob downwardly into the reduced part of 90 the keyhole. The latch 9 is then closed and moves over the lug or projection 7 until the upward locking edge 15 of the arm 13 is in line with the shoulder 8 of said lug or projection, when the arm 13 of the latch springs 95 inwardly automatically and secures the latch in locked position over the button or knob 12. When the latch is closed, as above described, the wall of the throat 10 draws the shank of 100 the button down into the reduced portion of

the keyhole-slot and in so doing draws upon the curtain to stretch the same taut, this action being due, as will be readily understood, to the eccentric arrangement of the keyhole-slot 5 and the peculiar form of the throat 10. In releasing the fastening the arm 13 is drawn outward until the shoulder of the lug or projection 7 is cleared, and the latch is then turned backwardly toward the right to fully expose 10 the keyhole-slot 6 and permit the curtain to be drawn downwardly and release the same from the curtain button or knob.

The improved fastening is simple in its construction and can be readily applied at a minimum cost. By its use a curtain is prevented 15 from becoming torn or worn at the points where it engages the curtain buttons or knobs, and the main advantage of the fastening is that a curtain will be reliably held in secured 20 position and cannot work loose and become detached.

Advantages in the proportions and dimensions may be resorted to without departing from the spirit of the invention.

Having thus described the invention, what 25 is claimed as new is—

A fastening for carriage-curtains comprising a plate having attaching-prongs projecting therefrom, said plate being formed with an eccentrically-arranged keyhole-slot adapted to register with a buttonhole in the curtain, a latch pivoted to said plate and formed with a throat to register with the lower portion of the keyhole-slot and to engage the shank of the curtain-button inserted therein 35 and the latch having a laterally-projecting arm, said latch being adapted to coact with said eccentric slot to draw the curtain taut, and a catch integral with and projecting from the plate, said catch being arranged to engage 40 the latch at the junction of the plate and the said arm to hold said latch in locking position.

In testimony whereof I affix my signature in presence of two witnesses.

CHARLES E. FLORES.
